UNITED STATES PATENT OFFICE

LOOMIS L. KELLY, OF ROANOKE, VIRGINIA; WILLIAM M. BRODIE ADMINISTRATOR OF
SAID LOOMIS L. KELLY, DECEASED

EXHAUST APPARATUS

Application filed August 22, 1930. Serial No. 477,128.

My invention relates to an exhaust apparatus for locomotive roundhouses and the like and it has for its principal object the provision of improved means adapted to be associated with the stack of a locomotive for conveying exhaust gases therefrom to the exterior of the roundhouse.

A principal feature of the invention consists in providing a series of relatively movable ducts for conveying the locomotive exhaust gases from the locomotive to the exterior of the building, said series comprising a duct mounted upon a horizontally movable carriage.

Another feature of the invention consists in providing two pivotally connected ducts, one of said ducts being connected to a horizontally movable carriage and having telescopically associated therewith a duct adapted to be moved into engagement with the stack of a locomotive.

Another feature of the invention consists in providing, in combination with an immovable duct, a series of relatively movable ducts, one of the ducts of said series being rigidly mounted upon a horizontally movable carriage.

A further feature of the invention resides in mounting upon the exterior of the duct connected to the horizontally movable carriage a motor provided with a shaft having a fan disposed within the duct.

A still further feature of the invention consists in providing the carriage duct with a recessed portion and in rigidly securing to the duct within the recess a motor having a shaft provided with a fan disposed within the duct.

Other and more specific features of the invention residing in advantageous forms, combinations and relations of parts will hereinafter appear and be pointed out in the claims.

In the drawings illustrating preferred embodiments of the drawings:

Figure 1 is a sectional view of a roundhouse illustrating one form of the smoke exhaust apparatus.

Figure 2 is an enlarged side elevational

view of a portion of the smoke exhaust apparatus illustrated in Figure 1.

Figure 3 is a view taken at right angles to the view in Figure 2.

Figure 4 is a vertical sectional view taken on line 4—4, Figure 3, the motor and fan being in elevation.

Figure 5 is a view corresponding to Figure 2 illustrating a modified form of the invention.

Figure 6 is a view corresponding to Figure 3 illustrating the modified form of the invention shown in Figure 5.

Figure 7 is a fragmentary sectional view taken on line 7—7, Figure 5.

Figure 8 is a side elevational view of another modified form of the invention.

Figure 9 is a fragmentary view partly in elevation and partly in section taken at right angles to the view illustrated in Figure 8.

Referring more particularly to the drawings 1 indicates the roundhouse which, as is well known, is provided with a plurality of stalls into which locomotives are adapted to be run for the purpose of repairs. In order to convey exhaust gases from the locomotive to the exterior of the roundhouse while the locomotive is being repaired, each of the stalls, one of which is shown in Figure 1, is equipped with an apparatus adapted to be operatively associated with the stack 2 of a locomotive diagrammatically illustrated and designated by the reference numeral 3.

The exhaust apparatus in each form in which it is illustrated in the drawings comprises a series of ducts which are relatively movable so that they may be operatively associated with the locomotive irrespective of whatever position, within certain limits, the latter may be brought to rest within the stall. In order that these series of ducts may be easily and conveniently moved one of them is connected to a horizontally movable carriage 4 which is provided with two pairs of rollers 5 adapted to rest upon and move along horizontally disposed beam members 6. These beam members which may advantageously be of I-section are disposed on opposite sides of the center line of the track upon which the locomotive is adapted to be moved

60

65

100

within the stall and while they may be supported in any convenient manner, they have been illustrated as resting upon the structural members 7 connected to any adjacent portion of the roundhouse.

In each form of the invention the carriage comprises two pairs of longitudinally extending frame members 8 and 9, respectively, which are preferably connected adjacent their ends by transversely extending frame members 10. The rollers 5 are positioned between the longitudinal frame members of each pair and are mounted upon shafts 11 which may be advantageously journaled in the latter. To provide convenient means for moving the carriage a sheave 12 is keyed to one of the shafts 11 and this sheave is provided with a flexible device such as an endless chain 13 so that it may be readily rotated by an operator from the floor of the roundhouse. It will, of course, be appreciated that one of the rollers 5 on the shaft upon which the sheave 12 is mounted must also be keyed to the shaft to effect movement of the carriage by rotation of the sheave. As may be clearly seen in Figure 3 the sheave 12 is spaced a sufficient distance from the carriage so that its operating chain will hang to one side of the associated locomotive.

In the form of the invention illustrated in Figures 1 to 4, inclusive, the duct which is connected to the carriage is designated by the reference numeral 14. At its upper end this duct is pivotally connected to a duct 15 which leads into and has communication with a duct 16 immovably mounted in the roof of the roundhouse. In order that the entire weight of the duct 15 will not be transmitted to the duct 14 the former is preferably counterbalanced by a weight 17 attached thereto by a chain or cable 18 which passes over a shaft or pulley 19 secured to any convenient portion of the roundhouse such as the roof. The upper end of the duct 15 terminates a relatively great distance above the lower end of the immovable duct 16 and is so disposed therein that the lower end thereof may be free to move with the duct 14 and carriage 4.

To permit free pivotal movement between the ducts 14 and 15 and at the same time to provide a relatively snug fit between the two, the upper portion of the former is spherically shaped, as at 20, and is adapted to be disposed within the lower portion of the latter which is preferably enlarged as at 21. The means for pivotally connecting the ducts may advantageously be a bolt 22 which passes through the center of the spherically shaped portion of the duct 14. The lower portion of the duct 15 is cylindrically shaped and its internal diameter is just slightly greater than the external diameter of the spherical portion of the duct 14. In this manner it will be seen that the angular relationship between the two ducts may be greatly varied and yet

the connection between the two is such that exhaust gases from the locomotive will be prevented from escaping into the roundhouse.

Secured to the lower end of the duct 14 is a plate member 23 having an aperture for receiving a vertically movable duct 24 adapted to telescope within the duct 14. In order to conveniently connect the plate member 23 and the duct 14 the latter is provided with a marginal flange 25 for receiving screws 26 or the like which pass through the plate. The lower end of the duct 24 is fashioned with a horizontally disposed laterally projecting flange 27 adapted to rest upon the stack of a locomotive.

As it is sometimes necessary to move the locomotive while it is in operative association with the exhaust apparatus, means is preferably provided whereby movement of the locomotive will induce movement of the apparatus. In the present embodiment of the invention this means comprises two pairs of members 28 and 29, respectively, which depend downwardly below the flange 27 on the duct 24. The members 28 are mounted within the duct 24 at the inner edge of the flange 27 and are adapted to extend into the stack of the locomotive while the members 29 are mounted adjacent the outer edge of the flange 27 and are adapted to be disposed on the outside of the cooperating stack. By providing two pairs of these members it will be appreciated that the amount the stack may move before coming into contact with one of them is very much less than the amount the locomotive could move, relatively to the duct, should only one pair be employed. The outer pair of the depending members are pivotally connected to the duct 24 by pins or the like 30 and by frangible pins 31 so that should the locomotive be moved beyond the limits of horizontal travel of the carriage, the force transmitted from the stack of the locomotive to the cooperating member of the outer pair will shear the frangible pin of that member, thus permitting the latter to assume an inoperative position and enable continued movement of the locomotive without damage to the exhaust apparatus. The inner pair of the depending members is also connected to the duct by frangible pins but since both members are disposed in the path of movement of the stack when the locomotive is moved in either direction each of them is connected by two of such pins 32 and 33. It will thus be appreciated that when the stack of the locomotive moves to the right as viewed in Figure 4 pin 32 of the left one of the inner members will be sheared while pin 33 of the right one will be sheared whereby the members are enabled to respectively rotate about the unsheared pins.

To obtain a tight fit between ducts 14 and 24 and yet permit relative vertical move-

ment between them a packing device is preferably employed which consists of a ring 34 and packing material 35. The packing ring may be conveniently secured by bolts 36 to the plate 23 adjacent the aperture formed therein for the reception of the duct 24.

While any suitable means may be employed for moving the telescoping duct 24 I prefer to employ mechanism which may be easily and quickly manipulated from the floor of the roundhouse. Thus the mechanism comprises a pair of drums 37 rigidly mounted on a shaft 38 which may be journaled in a bracket 39. As may be perceived this bracket is of U-shape and the legs thereof, in which the shaft 38 is mounted, are preferably secured to the duct 14 by bolts 40 and to the carriage frame by rivets 41. Connected to the drums 37 are flexible means 42, such as chains, cables or the like which are respectively attached to bars 43 secured to the flange 27 of the duct 24. These bars, while they afford convenient means to which the flexible chains 42 may be attached, are primarily designed to guide the duct 24 as it is being moved. For this reason the bars 43 pass through apertures in the marginal flange 25 formed on the duct 14, the flange being enlarged adjacent the apertures as at 44. The guide bars also pass through apertures formed in brackets 45 rigidly connected to the inner of the longitudinal frame members 8 and 9 and to the duct 14, these bracket members constituting the means for rigidly connecting the duct 14 to the carriage. Rigidly mounted upon the shaft 38 is a pinion 46 which meshes with a worm 47 formed on a shaft 48 mounted in a bracket 49 which is secured by any suitable means to the bracket member 39. Keyed to the shaft 48 is a sheave 50 equipped with an endless chain 51 which extends downwardly so that it may be readily grasped by an operator on the floor of the roundhouse. So that the lower end of the chain will be spaced from the side of the locomotive it is led over a pulley 52 carried by an arm 53 which extends downwardly and outwardly from the bracket 39 and is suitably braced by a member 54 secured to the carriage 4. It will thus be seen that by rotating the shaft 38 upon which the drums 37 are mounted through the intermediacy of the worm and pinion gear, the sheave 50 and the chain 51, the telescoping duct may be moved vertically whereby it may be brought into operative association with locomotives having stacks of different heights.

For inducing a draft within the duct a fan 55 is disposed within the duct 14 which is operatively connected to a motor 56 by a shaft 57. In order that the axis of rotation of the fan will be parallel to the axis of that portion of the duct immediately adjacent the duct 14 is provided with an elbow or offset portion 58. Instead of securing the

motor to the carriage it is preferably secured to the duct 14 within a recessed portion 59. By positioning the motor within the recess 59 it will be perceived that the motor and fan are in such close proximity that the fan may be mounted on the motor shaft thereby eliminating the necessity of employing an extension shaft and the bearings which would be required should such a shaft be used.

Instead of connecting the fan directly to the motor shaft it is preferred to connect it to a collar 60 which is mounted upon the shaft. This collar is formed with a plurality of fins 61, preferably radially arranged, which serve, when the motor is in operation, to agitate the air surrounding the motor to prevent it from becoming overheated due to it being mounted directly upon the duct and which serve, when the motor is not in operation, to radiate or dissipate heat which would ordinarily be transmitted to the latter through the shaft. As a further safeguard in preventing the transmission of excessive heat to the motor, the walls of the recessed portion 59 are covered with asbestos or other heat resisting material and, as shown at 60^a, similar material may advantageously be interposed between the hub of the fan and the collar 60.

With the exception of certain features of construction to be hereinafter described the apparatus illustrated in Figures 5 to 7, inclusive, is substantially the same as that disclosed in Figures 1 to 4, inclusive. Corresponding parts of the apparatus have, therefore, been designated by similar reference numerals. The manner of pivotally connecting the ducts 14 and 15 is slightly different in Figures 5 to 7, inclusive, in that instead of connecting them by means which is disposed centrally of the ducts they are connected by a pivot bolt or the like 62 disposed to one side of the ducts. For this purpose the lower end of duct 15 is provided with a casting 63 formed as a section of an annulus and having a laterally projecting lug 64 for receiving the pivot bolt 62. The annulus is defined by two planes which are disposed at acute angles to each other and are substantially radial with respect to the pivotal axis of the casting. The upper portion of the duct 14 is offset with respect to the lower portion thereof and is adapted to extend within the casting 63 in all positions that the latter may assume, the duct 14 being formed with laterally projecting trunnions 65 for receiving the pivot bolt 62.

In this form of the invention the duct 14 is not provided with a recess in which the motor is secured but instead the latter is secured to the exterior of the duct below the offset upper portion thereof so that the axis of rotation of the motor shaft 66 is substantially vertical. Secured to the motor shaft by a coupling 67 is a shaft 68 which extends

upwardly into the duct 14 within a cylindrically shaped portion 69 which is preferably formed integral with the duct. A plurality of bearings 70 are preferably provided for the shaft 68 to prevent vibration thereof. Mounted upon the upper end of the shaft within the duct 14 is a fan 71 for inducing a draft within the ducts. Immediately below the upper bearing 70 the cylindrical portion 10 69 is provided with a plurality of passageways 72 whereby cool air may be drawn through the cylindrical portion into the duct to prevent overheating of this bearing. If desired the cylindrical portion may be rigidified or reinforced by a web 73.

Since the diameter of the duct 14 illustrated in Figures 5 to 7, inclusive, is less than that of the corresponding duct illustrated in Figures 1 to 4, inclusive, the bottom plate 23 may be omitted in this form 20 of the invention and the packing ring 34 may be secured directly to the lower marginal flange 25 of the duct.

The means by which the carriage is moved horizontally and the means by which the telescoping duct 24 is moved vertically are the same in this form of the invention as in the form illustrated in Figures 1 to 4, inclusive.

20 In the form of the invention illustrated in Figures 8 and 9 there is provided an immovable duct 74 mounted in the roof of the roundhouse and a duct 75 which is pivoted at its upper end to the first-named duct. 25 The duct 75 may be conveniently made in two sections which are welded or otherwise secured together as at 76. The upper end of the upper section of the duct 75 is offset the same as and formed similarly to the upper portion of the duct 14 illustrated in Figures 5 to 7, inclusive, the motor being mounted and associated with the duct 75 in the same manner as with the duct 14.

30 The lower end of the duct 75 is provided with a flexible bellows 77 which may be of any suitable material, such as treated canvas, woven asbestos, light metal or the like. The bellows is supported by and secured to an apertured plate or the like 78 provided with a plurality of upwardly and outwardly extending arms 79 secured to the transverse frame members of the carriage 4. To protect the bellows from the hot gases which pass through the ducts from the locomotive 35 a tubular shell 80 may be advantageously provided, the shell being connected to the plate 78.

To guide the lower end of the duct 75 blocks or brackets 81 may be employed which are formed with inwardly projecting trunnions 82 which pass through the duct. The blocks are also fashioned with apertures through which the guide bars 43 of the telescoping duct 24 pass, the guide bars being associated 40 with the carriage in the same manner as in

other forms of the invention. It will thus be perceived that when the carriage 4 is moved horizontally causing the duct 75 to rotate about the point at which it is pivotally connected to the immovable duct 74 the lower end of the duct 75 will be guided by the blocks 81 cooperating with the guide bars 43.

Although the mechanism for moving the telescoping duct 24 vertically is the same as that disclosed in the other forms of the invention, instead of mounting this mechanism on a bracket or the like above the carriage it is mounted directly on the latter at one end thereof. The flexible chain or cable 42 is not, however, connected to the upper ends of the guide bars 43 but instead is connected to the duct 24 adjacent the lower ends of the guide bars, being led over sheaves or the like 50 83 mounted upon the frame members of the carriage.

From the foregoing it will be perceived that the invention which has been disclosed in several forms is so constructed that it may be easily and quickly manipulated to be brought into operative association with a locomotive to conduct the exhaust gases therefrom to the exterior of the roundhouse.

I claim:

1. In an exhaust apparatus for locomotive roundhouses, the combination with an immovably mounted duct, of a horizontally movable carriage, and a series of normally upright ducts depending from adjacent the roof of the roundhouse and the upper end of said series having communication with said immovable duct, the lower end of said series of ducts being connected to and movable with said carriage and the latter being movable with respect to the said upper end of said series whereby said ducts may be moved into operative association with the stack of a locomotive.

2. An exhaust apparatus for a locomotive roundhouse involving a horizontally movable carriage, a duct mounted upon and movable with said carriage, means telescopically arranged with said duct adapted to be operatively associated with the stack of a locomotive, and a duct pivotally connected to said first-mentioned duct for conveying the locomotive exhaust gases to the exterior of the building.

3. An exhaust apparatus for a locomotive roundhouse involving two pivotally connected ducts, a horizontally movable carriage, one of said ducts being mounted upon and movable with the carriage and with respect to the other of said ducts, and means telescopically arranged with said ducts for operative association with the stack of a locomotive.

4. In an exhaust apparatus for a locomotive roundhouse, the combination with an immovably mounted duct, of a horizontally movable carriage, a series of relatively movable normally upright ducts depending from adja- 130

- cent the roof of the roundhouse and the upper end of said series having communication with said immovable duct, said series of ducts being connected to and movable with said carriage and the latter being movable with respect to the said upper end of said series, said series including a substantially vertically movable telescoping duct adapted to be operatively associated with the stack of a locomotive, and a motor mounted on the exterior of one of the ducts of said series and having a shaft provided with a fan disposed within one of said ducts for inducing a draft therein.
5. An exhaust apparatus for a locomotive roundhouse involving two pivotally connected ducts, a horizontally movable carriage, one of said ducts being mounted upon and movable with the carriage and with respect to the other of said ducts, means telescopically associated with said ducts for establishing communication between the latter and the stack of a locomotive, a motor mounted upon the exterior of one of said ducts, and a fan within one of said ducts and operatively connected with said motor.
6. In an exhaust apparatus for a locomotive roundhouse, the combination with overhead beam members extending parallel with and disposed on opposite sides of the center line of the track upon which a locomotive is adapted to move, of a carriage provided with a plurality of rollers resting upon and movable along said beam members, a series of normally upright ducts depending from adjacent the roof of the roundhouse and the upper end of said series having communication with an opening in said roof, the lower end of said series of ducts being connected to and movable with said carriage and with respect to the said upper end of said series, and means for moving said carriage to bring the lower end of said series of ducts into registration with the stack of the locomotive, said means involving a shaft revolvably mounted on said carriage and upon which one of said rollers is rigidly mounted and a sheave keyed to said shaft for receiving flexible means for rotating the latter.
7. In an exhaust apparatus for a locomotive roundhouse, the combination with an immovably mounted duct, of a pair of beam members, a carriage provided with a plurality of rollers resting upon and movable along said beam members, a series of relatively movable normally upright ducts depending from adjacent the roof of the roundhouse and the upper end of said series having communication with said immovable duct, said series of ducts being connected to and movable with said carriage, means for moving said carriage to bring the lower end of said series of ducts into registration with the stack of a locomotive, and a motor mounted on the exterior of one of said movable ducts and provided with a shaft having a fan disposed

within one of said ducts for inducing a draft within said series of ducts.

8. In an exhaust apparatus for a locomotive roundhouse, the combination with overhead beam members extending parallel with and disposed on opposite sides of the center line of the track upon which a locomotive is adapted to move, of a carriage comprising two pairs of longitudinal frame members, rollers interposed between the members of each pair adapted to rest upon and move along said beam members, and a series of relatively movable ducts for conveying exhaust gases from a locomotive stack to the exterior of the building, said series involving a duct connected to and movable with said carriage.

9. In an exhaust apparatus for a locomotive roundhouse, the combination with overhead beam members extending parallel with and disposed on opposite sides of the center line of the track upon which a locomotive is adapted to move, of a carriage comprising two pairs of longitudinal frame members and rollers interposed between the members of each pair adapted to rest upon and move along said beam members, and a series of relatively movable ducts for conveying exhaust gases from a locomotive stack to the exterior of the building, said series involving a duct mounted upon and movable with said carriage, and means for moving said carriage to bring said series of ducts into communication with the stack of the locomotive, said means involving a shaft revolvably mounted on said carriage and upon which one of said rollers is mounted and a sheave keyed to said shaft for receiving flexible means for operating the latter.

10. An exhaust apparatus for a locomotive roundhouse involving a horizontally movable carriage, a series of ducts for conveying exhaust gases from a locomotive to the exterior of the roundhouse, said series including a duct mounted upon and movable with said carriage and a vertically telescoping duct cooperable with the stack of the locomotive, and means for guiding said last-named duct involving brackets secured to said carriage and bars secured to said duct.

11. An exhaust apparatus for a locomotive roundhouse involving a horizontally movable carriage, a series of ducts for conveying exhaust gases from the locomotive to the exterior of the roundhouse, said series including a duct mounted upon and movable with said carriage and a vertically telescoping duct cooperable with the stack of the locomotive, said last-named duct being provided at its lower end with an outwardly projecting substantially horizontally disposed marginal flange for engagement with the stack of the locomotive, and two pairs of pivotally mounted members depending from said flange, the members of one pair being disposed adjacent

the inner edges of the flange and those of the other pair being disposed adjacent the outer edges of the flange, and frangible pins for limiting pivotal movement of said members, 5 the stack of the locomotive being adapted to be positioned between said pairs of members and being cooperable therewith to cause movement of said series of ducts upon movement of the locomotive.

- 10 12. An exhaust apparatus for a locomotive roundhouse involving a series of movable ducts for conveying exhaust gases from a locomotive to the exterior of the roundhouse, said series of ducts including a vertical telescoping duct cooperable with the stack of the locomotive, said last-named duct being provided at its lower end with an outwardly projecting substantially horizontally disposed flange for engagement with the said stack, 15 members respectively disposed within said duct on opposite sides thereof and projecting downwardly therefrom beyond said horizontal flange, each of said members being connected to said duct by two frangible pins, said 20 members being adapted to project downwardly within the stack of the locomotive.

13. A locomotive smoke apparatus comprising an immovably mounted duct, a horizontally movable carriage, a series of ducts 30 for conveying exhaust gases from the stack of a locomotive to said immovable duct, said series including two pivotally connected ducts, one of said ducts being immovably mounted on the carriage, and a motor mounted upon the exterior of said last-named duct and provided with a shaft having a fan disposed within one of said ducts.

14. An exhaust apparatus for a locomotive roundhouse involving an immovable duct, a 40 horizontally movable carriage provided with a relatively immovable duct, the latter having an extensible section adapted to be operatively associated with the stack of a locomotive, and a duct pivotally connected to said carriage duct and having communication with said immovable duct, and a motor mounted on the exterior of said carriage duct and having a shaft provided with a fan disposed within said duct.

50 15. An exhaust apparatus for a locomotive roundhouse comprising a horizontally movable carriage, a series of ducts for conveying exhaust gases from the stack of a locomotive to the exterior of the roundhouse, said series 55 of ducts including a duct mounted upon and movable with said carriage and a vertically movable duct telescopically associated with the carriage duct, bracket members for rigidly connecting the latter to said carriage, and 60 members secured to said telescoping duct and cooperable with said bracket members for guiding said last-named duct.

16. An exhaust apparatus for a locomotive roundhouse comprising a horizontally movable carriage, a series of ducts for conveying

exhaust gases from the stack of a locomotive to the exterior of the roundhouse, said series of ducts including a duct rigidly secured to said carriage and a duct telescopically associated with the carriage duct, the latter having laterally projecting apertured portions, and members secured to said telescoping duct and cooperable with said apertured portions for guiding said last-named duct.

70 17. An exhaust apparatus for a locomotive roundhouse comprising a horizontally movable carriage, a series of ducts for conveying exhaust gases from the stack of a locomotive to the exterior of the roundhouse, said series of ducts comprising a duct secured to the carriage and a vertically movable duct telescopically associated with the carriage duct, and mechanism for moving said telescoping duct comprising a pair of drums, flexible means connecting said drums and duct, and means for rotating said drums.

75 18. An exhaust apparatus for a locomotive roundhouse comprising a horizontally movable carriage, a series of ducts for conveying exhaust gases from the stack of a locomotive to the exterior of the roundhouse, said series of ducts including a duct connected to said carriage and a vertically movable duct telescopically associated with the carriage duct, and mechanism for moving said telescoping duct comprising a horizontally disposed shaft provided with a plurality of drums, flexible means connecting said drums and duct, and means for rotating said shaft involving a sheave and cooperating flexible device.

80 19. An exhaust apparatus for a locomotive roundhouse comprising a horizontally movable carriage, a series of ducts for conveying exhaust gases from the stack of a locomotive to the exterior of the roundhouse, said series of ducts comprising a duct immovably mounted on said carriage and a vertically movable duct telescopically associated with the carriage duct, and means for moving said telescoping duct comprising a shaft provided with a plurality of drums, flexible means connecting said duct and drums, a sheave for rotating said shaft, and worm and pinion gears operatively interposed between said shaft and sheave.

85 110 20. An exhaust apparatus for a locomotive roundhouse comprising a horizontally movable carriage, a series of ducts for conveying exhaust gases from the stack of a locomotive to the exterior of the roundhouse, said series of ducts including a duct immovably mounted upon said carriage and a vertically movable duct telescopically associated with the carriage duct, and means for moving said telescoping duct comprising a shaft provided with a plurality of drums, a bracket device mounted upon said immovable duct, said shaft being journaled in said bracket device, guide bars connected to said duct,

flexible means connecting said guide bars and drums, and means for rotating said drums.

21. An exhaust apparatus for a locomotive roundhouse involving a movable duct adapted to have communication with the stack of a locomotive, a motor rigidly mounted upon the exterior of said duct, and a fan disposed within said duct, said motor and fan being operatively connected by a shaft, the portion of the shaft between the motor and duct being provided with a plurality of fins.

22. An exhaust apparatus for a locomotive roundhouse involving a movable duct adapted to have communication with the stack of a locomotive, a motor rigidly mounted upon the exterior of said duct, said motor having a shaft projecting into said duct, a fan rigidly mounted on said shaft within the duct, and means mounted upon said shaft for agitating the air adjacent the motor.

23. An exhaust apparatus for a locomotive roundhouse involving a movable duct adapted to have communication with the stack of a locomotive, said duct being provided with a recessed portion, and a motor rigidly secured to the exterior of said duct within the recessed portion thereof, and a fan disposed within the duct, said fan and motor being operatively connected by a shaft.

24. An exhaust apparatus for a locomotive roundhouse involving a movable duct adapted to have communication with the stack of a locomotive, said duct being offset intermediate its ends and provided adjacent the offset with a recess, and a motor rigidly mounted on the exterior of said duct within said recess, said motor having a shaft provided with a fan disposed within said duct.

25. An exhaust apparatus for a locomotive roundhouse involving a horizontally movable carriage, a series of ducts one of which is connected to the carriage and is provided with a recessed portion, and a motor secured to said duct within the recess and being provided with a shaft having a fan disposed within the ducts.

26. An exhaust apparatus for a locomotive roundhouse involving a conduit comprising a series of relatively movable ducts, one of said ducts being angularly movable with respect to an adjacent duct and another of said ducts being telescopically associated with an adjacent duct, and means for inducing a draft in the conduit comprising a fan disposed within one of said ducts and a motor rigidly mounted on the exterior of one of said ducts.

27. An exhaust apparatus for a locomotive roundhouse involving a conduit comprising a series of relatively movable conduits, a horizontally movable carriage, one of said conduits being connected to the carriage and

being angularly movable with respect to an adjacent duct, another of said ducts being telescopically associated with the duct connected to the carriage, and means for inducing a draft in the conduit comprising a fan disposed within one of said ducts and a motor rigidly mounted on the exterior of one of said ducts.

28. An exhaust apparatus for a locomotive roundhouse comprising a conduit involving an angularly movable duct and a telescopically movable duct, one of said ducts being provided with a recessed portion, a motor rigidly mounted on the exterior of said last-named duct within the recess, and a fan disposed within one of said ducts and operatively connected to the motor for inducing a draft in the conduit.

29. An exhaust apparatus for a locomotive roundhouse comprising a conduit involving a series of angularly movable and telescopically associated ducts, a fan disposed within the conduit, a motor rigidly mounted on the exterior of one of said ducts, and a shaft operatively connecting the fan and motor, the last-named duct having an inwardly extending substantially cylindrical portion in which said shaft is disposed whereby air may be drawn by the fan into the conduit.

30. An exhaust apparatus for a locomotive roundhouse involving a conduit comprising a series of relatively movable ducts, a horizontally movable carriage, one of said ducts being connected to the carriage and being angularly movable with respect to an adjacent duct, another of said ducts being telescopically associated with the duct connected to the carriage, a motor mounted on the exterior of the carriage duct, a fan disposed within the conduit, and a substantially vertical shaft operatively connecting the fan and motor.

31. An exhaust apparatus for a locomotive roundhouse comprising a conduit involving a series of ducts, one of said ducts being angularly movable and another being telescopically movable, a motor rigidly mounted on the exterior of one of said ducts, a fan disposed within the conduit and a shaft operatively connecting the fan and motor, the axis of said shaft being substantially parallel with the major axis of the duct on which the motor is mounted.

In testimony whereof I affix my signature.

LOOMIS L. KELLY.
